UNITED STATES PATENT OFFICE.

HERBERT R. PALMER, OF CLEVELAND, OHIO.

LAMP.

1,272,509.

Specification of Letters Patent. Patented July 16, 1918.

Application filed February 8, 1917. Serial No. 147,289.

To all whom it may concern:

Be it known that I, HERBERT R. PALMER, a citizen of the United States, residing at Cleveland, in the county of Cuyahoga and State of Ohio, have invented a certain new and useful Improvement in Lamps, of which the following is a specification.

This invention relates to lamps of the so-called headlight type, and it has particular reference to the construction of the front of the lamp, or to a device adapted to be attached to the face of the lamp casing to operate conjointly with the other elements of the lamp for controlling the glare and increasing the efficiency of the lamp.

The improvement is applicable to the headlights at present in common use on automobiles, motor-cycles, motor boats, and other vehicles, and also to an improved type of lamp which I have invented, and which is the subject of another application for Letters Patent.

The lamps in common use on vehicles are provided with a parabolic reflector located back of the light member for projecting the rays over a more or less broad field in advance of the vehicle, and while they may be effective in lighting the way, they produce a glare which is annoying. The object of the present invention is the provision of simple and effective means for automatically obviating or deflecting the glare without materially decreasing the illuminating effect of the lamp, and to direct certain of the light rays over a field where they are most desired.

I am aware that a number of patents have been granted for lamps embodying the arrangement of a series of longitudinal cells in front of the lamp for deflecting the glare, and that therefore the broad principle is not new. The present invention however consists in the novel construction whereby longitudinal cells are provided in front of the light member and arranged around a core, the said core being provided with a member so constructed as to perform, in conjunction with other elements, certain desirable functions that are hereinafter fully explained.

In the accompanying drawings forming a part of the specification Figure 1 is a front view of a lamp embodying the improvement.

Fig. 2 is a section on line 2-2 of Fig. 1.

Fig. 3 is a central vertical section of a modified core member.

Fig. 4 is a front view of said modification.

Fig. 5 is a top view of the core member, and Fig. 6 is a fragmentary view showing the longitudinal cell construction in detail.

Throughout the several figures of the drawings and in the description similar characters of reference are employed to designate similar parts.

A preferred embodiment of the invention provides a device so constructed as to make it adaptable for attachment to the ordinary lamp at present in common use. This construction, as shown in the several figures of the drawings, provides a casing member 1 adapted to extend outward from the front of the lamp, being attached to the lamp body 2 by a ring 3, said ring engaging a flange 1^a. The casing 1 is provided with a transparent outer face 4, and has a longitudinal tubular core 5. The annular space between the core and the wall of the casing 1 is occupied by a series of longitudinal cells 6. The novel construction, arrangement, and mode of assembling the cells 6 forms an important factor of the invention. The said cells are preferably formed by three 80 continuous thin sheet metal members, a fluted or corrugated member 7 interposed between two plain members 8 and 8^a, see Fig. 6 for detail of construction. The three members 7, 8, and 8^a are assembled as 85 shown, in a strip of predetermined length. The strip thus formed is wound in a coil around the core 5 and is of sufficient length to entirely fill the annular space between the core and the casing 1 when tightly coiled. 90 The corrugations in the member 7 form the longitudinal cells 6, and the members 8 and 8^a form supports for the member 7, thereby making a firm, durable, and economical construction of longitudinal cells the walls of 95 which intercept and kill the glare rays indicated by a and a' Fig. 2. The light rays b and b' are projected by the reflector 9 in horizontal rays c and c' through the cells 6. The same result can be obtained by combining one plain member and the corrugated member, and when coiled 8^a would be a continuation of the member 8, the member 7 100 lying between the coils.

The forward end of the core 5 is provided with a glass member 10 having a plain interior face and a prismatic outer face 10^a. The light rays d strike the member 10 and are projected downward in the field d'. The prismatic face 10^a is preferably formed 105

120

with surfaces in a variety of angles, as shown, thereby diverting the rays d' at different angles as shown.

It will be seen that by this arrangement 5 and combination of elements the light rays d' will fall on the roadway over an area, in front of the vehicle, extending from close proximity to said vehicle over a considerable field forward thereof, and that the light rays 10 c and c' are projected in horizontal planes, or straight ahead indefinitely. Therefore by the improved construction the light rays from the light member 1 are controlled and diverted over a field of utility most desired 15 and without the glare annoyance.

The modification illustrated in Figs. 3 and 4 lies wholly in the light deflecting member located in the core 5. This member has the prismatic formation 10^b on the outer face 20 surrounding a central, plain or concave portion 10^c which is adapted to receive the central rays e and project them direct as shown in Fig. 3, while the function of the prismatic portion 10^b is the same as that of 10^a as 25 shown in Fig. 2.

What I claim and desire to secure by Letters Patent is:

1. In a lamp the combination of a casing 30 extending from the front of the lamp body; a tubular core member in said casing; a longitudinally corrugated member coiled around said core thereby forming a series of lon-

gitudinal cells in said casing; and a glass member in the forward end of said tubular core, the outer face of said glass member 35 being prismatic and the inner face plain.

2. In a lamp the combination of a casing extending from the front of the lamp body; a core member in said casing; a series of longitudinal cells in said casing surrounding 40 the core, said cells being formed by a corrugated strip of material supported by a plain strip coiled around the core; and a glass member in the forward end of said core, the outer face of said glass member being prismatic 45 and the inner face plain.

3. In a lamp the combination of a casing extending from the front of the lamp body; a series of longitudinal cells in said casing; 50 a tubular core in said casing, the longitudinal cells surrounding said core; and a light deflecting member in said core, the outer face of said light deflecting member having a plain central portion surrounded by 55 prisms.

4. In a lamp the combination of a casing attached to the front of the lamp; a tubular core in said casing; a coil of longitudinal cells surrounding said core; and a light deflecting member in said core, the outer 60 face of said light deflecting member having a plain central portion surrounded by prisms, and the inner face being plain.

HERBERT R. PALMER.
